MEANS FOR OPERATING RING FLYERS IN
MACHINES FOR SPINNING AND DOUBLING
COTTON AND OTHER FIBROUS SUB-
STANCES

Wilfred Whiteley, Elland, England

Application April 20, 1934, Serial No. 721,590
In Great Britain April 27, 1933

7 Claims. (Cl. 118—47)

The invention relates to that type of yarn spinning known as the ring flyer system, wherein the spindle is rotated solely by the thread being spun or twisted, an example of which will be found in the British Patent Specification No. 26,228 of 1904. In this system it is usual to use a revolving ring or bush which hereinafter will be termed a ring flyer driven from the usual tin rollers or otherwise, and of sufficient internal diameter, to accommodate the package of yarn to be built on the spindle in the form of a cop or bobbin. It is also known that to revolve a ring flyer on the necessary large bearing required for the above-mentioned conditions, the amount of power required is a serious handicap and a drawback due mainly to the viscosity of the lubricating oil, and for the purpose of mitigating this object ball bearings have also been tried.

In previous practice, it is customary for the full tension of the driving bands or tapes to pull upon these bearings over approximately one half of the circumference of the ring flyer, consequently the greater the tension or pull the greater is the friction created thereby between said ring flyer and its bearing.

The object of the present invention is an improved system of driving said ring flyers whereby the conditions aforesaid are obviated, the tension of the driving bands exert no pull on the flyer bearings, no lubrication of said bearings is necessary consequently no soiling or contamination of the yarn by lubricant can occur; friction in the bearings is reduced or eliminated; considerable economies in power are effected, and the flyers may be run at a greatly increased rotary speed.

According to the present invention, the ring flyers are rotated by a balanced drive. By this is meant that the frictional contact of the driving bands or tapes and the motive power thereof, is applied at two diametrically opposite segmental parts only of the wharve of the ring flyers, whereby the pressure and force applied to one side of the flyer is balanced by equal conditions on the opposite side. Also by means of slightly increasing the relative height of the tension pulley wharves the bands or tapes can be made to carry the weight of the ring flyers, whereby the latter may be said to be in a floating condition.

Alternatively, a balanced drive may be provided for the ring flyers by mounting them without any support bearings, the flyers being held in their operative positions against antifriction

pulleys by the tension of the driving bands and two segmental portions of the flanges of said pulleys.

Means are also provided on the fixed or bolster rail, whereby the whole of the tension pulleys can be moved laterally into the relative different position necessitated by changing the bands or tapes when altering the direction of rotation of the ring flyers, and for holding a part of said means in the operative position by the tension of the driving band.

I attain these objects by the means illustrated in the accompanying drawings, in which:—

Fig. 1 is a front elevation of a fragmentary part of a ring flyer spinning machine, showing the invention applied thereto.

Fig. 2 is a plan view of Fig. 1.

Fig. 3 is a sectional end view of Fig. 2 on the line III—III of Fig. 2.

Fig. 4 is a similar view to Fig. 2, showing the driving bands arranged for giving an opposite twist of yarn as opposed to the twist given by the driving bands in Fig. 2.

Fig. 5 is a plan view of an alternative method for driving the ring flyers.

Fig. 6 is an end view of Fig. 5 and the mounting of the driving means, drawn to a larger scale.

Fig. 7 is an elevation of a ring flyer constructed according to the present invention.

Fig. 8 is a view of the underside of the ring shown in Fig. 7.

Fig. 9 is a full size sectional elevation of a tension pulley and means for mounting same on the fixed or like bolster rail of the machine.

Fig. 10 is an end view, partly in section, of alternative means to that shown in Fig. 9 of mounting the tension pulley on the bolster rail.

Fig. 11 is a front elevation of a fragment of an auxiliary rail associated with a normal bolster rail, showing means whereby the auxiliary rail may be adjusted relative to the bolster rail and locked thereto.

Similar letters refer to similar parts throughout the several views.

With reference to the drawings, see Figs. 1, 2, 3, 4, 7, 8, 9, 10 and 11. A is the machine frame. B, C, are the customary tin rollers, D the driving bands or tapes passing over said rollers for rotating the ring flyers E mounted on the usual bearings F fitting apertures G in the bolster rail H. J is a lifter rail on which are mounted the spindles K on which are wound the cops or bobbins of yarn.

In order to obtain the aforesaid balanced drive

for the ring flyers E with particular reference to Figs. 1, 2, 3 of the drawings, an antifriction or tension pulley L is employed, the wharve of which is less in diameter than the wharves of the flyers. The said tension pulleys correspond in number with the number of ring flyers and each pulley is supported on a footstep M housed in an oil reservoir N for lubricating said pulley bearing, carried by a spring bracket P secured to the front of the rail H, or, to an adjustable auxiliary rail or bar H¹ bolted thereto. This spring P is for the purpose of taking up any stretch of the spindle band. Interposed between the outward and the inward portions of each band D at a point intermediate of the roller C and pulley L is situated the flyer E and its bearing F in the rail H. The upper surface of the rollers B, C, the wharves of the flyers E and the wharves of the tension pulleys L are approximately in the same horizontal plane with the bands D returning from the flyer to the roller B at right angles to the latter, and by a different angle on returning from roller C to said flyer. By bisecting the angle formed by the outward and inward portions of said band D as shown by the broken line in Fig. 2 of the drawings, the correct position is given to the pulleys L relative to the opposing flyers to ensure to the bands an uniform amount of segmental contact with the wharves thereof by the driving band, for giving the desired balanced drive.

Alternatively (see Fig. 10 of the drawings), in place of the housing of the pulley L being supported by a spring bracket as shown in Fig. 9, it may be carried by a flap R hinging at S on the rail H¹. The flap is provided with a stop T to prevent the tension on the driving band from raising the wharve of the tension pulley above the plane of the wharve of the flyer. Should the band become slack by any means the weight of said pulley and its housing will move the pulley out of the vertical and take up said slack, at the same time it will give warning by its position of the condition of the band D.

By arranging the rings E slightly below the horizontal plane of both the rollers B, C, and of the pulleys L, the tension of the driving bands is adapted to raise said rings until their castellated bases are clear of their bearings, when said rings may be said to revolve in a floating condition, as clearly shown in Fig. 10 of the drawings.

Where it is desired to dispense with bearings for the flyers (see Figs. 5 and 6 of the drawings) the flyers E are held in position against the antifriction or like pulleys L solely by the pull of the driving bands D, each ring flyer being in frictional contact with two of the said pulleys L, a flange U on the flyer overlapping the top of the pulley; the latter lends support to said flyer and is maintained in its operative position by the pull of the band as before described.

When the twist given to the yarn is required to be reversed, the bands D between the roller C and the flyers are turned, causing the direction of drive of the flyers E to be reversed (as clearly shown by arrows in Fig. 4 of the drawings); this gives an opposite twist to the yarn being spun.

In order to preserve the angle of engagement by the bands D with the wharves of the flyers according to whether a right or a left hand twist is to be given to the yarn, the rail H¹ is pro-

vided near each end with a slot V within which functions an eccentric W provided with a handle X for rotating same, the axle of eccentric W being housed in the bolster rail. The turning of one of these handles rotates the eccentric in its housing in rail H¹ causing said rail to be moved to the right or left, as shown in broken lines in Fig. 11 of the drawings, for the purposes aforesaid. Bolts Y operating in slots Z in the rail H¹ are adapted to lock said rail in 10 position after adjustment.

The ring flyer is preferably composed of vulcanite, ebonite or other suitable light material, but it may be made of metal, or a combination of metal and other material such as an aluminum flyer with a vulcanite inner bush, or a vulcanite flyer with a metal wharve, and castellations E¹ may be formed on the underside of said flyer for reducing the friction thereof when in contact with its bearing. E² are thread guides 20 fixed on opposite sides in the ring flyer.

What I claim as my invention, and desire to secure by Letters Patent, is:—

1. A spinning machine of the class described having in combination, driving rollers, a ring flyer axially movable on its bearing, a pulley associated with the ring flyer, and a driving band passing over said rollers and having portions engaging the pulley and opposite sides of the ring flyer, said ring flyer in its inoperative position, being disposed below the horizontal plane of the rollers and the pulley, whereby upon the operation of the machine, the tension of the driving band acts to move the ring flyer axially to rotate and support the same. 30

2. A spinning machine of the class described having in combination, driving rollers, a ring flyer axially movable on its bearing, a pulley having its wharve of less diameter than the wharve of the ring flyer, and a driving band 40 passing over said rollers and having horizontal portions engaging the pulley and opposite sides of the ring flyer, the band engaging portion of the ring flyer, when the latter is in its inoperative position, being disposed below the horizontal plane of the rollers and the pulley whereby upon the operation of the machine, the tension of the driving band acts to move the ring flyer axially to rotate and support the same. 45

3. A spinning machine of the class described having in combination, driving rollers, a ring flyer axially movable on its bearing, a pulley having its wharve of less diameter than the wharve of the ring flyer, a driving band passing over said rollers and having horizontal portions 55 engaging the pulley and opposite sides of the ring flyer, said ring flyer, in its inoperative position being disposed below the horizontal plane of the roller and the pulley, whereby upon the actuation of the machine, the tension of the driving band acts to move the ring flyer axially to rotate and support the same, and means connecting the pulley to the machine to maintain a uniform tension on the driving band. 60

4. A spinning machine of the class described having in combination, driving rollers, a ring flyer axially movable on its bearing, a pulley having its wharve of less diameter than the wharve of the ring flyer, a driving band passing over said rollers and having horizontal portions 70 engaging the pulley and opposite sides of the ring flyer, said ring flyer, in its inoperative position being disposed below the horizontal plane of the roller and the pulley, whereby upon the actuation of the machine, the tension of the 75

5

10

15

20

driving bands acts to move the ring flyer axially to rotate and support the same, and a yieldable member connecting the pulley to the machine, said yieldable member acting to maintain a uniform tension on the driving band.

5. A spinning machine of the class described having in combination, driving rollers, a ring flyer axially movable on its bearings, a pulley having its wharve of less diameter than the wharve of the ring flyer, a driving band passing over said rollers and having horizontal portions engaging the pulley and opposite sides of the ring flyer, said ring flyer, in its inoperative position, being disposed below the horizontal plane of the roller and the pulley, whereby upon the actuation of the machine, the tension of the driving band acts to move the ring flyer axially to rotate and support the same, a yieldable member connecting the pulley to the machine for maintaining a uniform tension on the driving band, a foot step mounted on the yieldable member for supporting the pulley, and means for lubricating said foot step.

6. A spinning machine of the class described having in combination, driving rollers, a ring flyer axially movable on its bearing, a pulley having its wharve of less diameter than the wharve of the ring flyer, a driving band pass-

ing over said rollers and having horizontal portions engaging the pulley and opposite sides of the ring flyer, said ring flyer, in its inoperative position, being disposed below the horizontal plane of the roller and the pulley, whereby upon the actuation of the machine, the tension of the driving bands acts to move the ring flyer axially to rotate and support the same, means for reversing the twist given to the yarn, and means for maintaining the angle of engagement of the bands on the ring flyer after reversal of the yarn.

7. A spinning machine of the class described having in combination, driving rollers, a ring flyer axially movable on its bearing, a pulley having its wharve of less diameter than the wharve of the ring flyer, a driving band passing over said rollers and having horizontal portions engaging the pulley and opposite sides of the ring flyer, said ring flyer, in its inoperative position, being disposed below the horizontal plane of the roller and the pulley, whereby upon the actuation of the machine, the tension of the driving band acts to move the ring flyer axially to rotate and support the same, and a hinged member supporting said pulley, and connected to the machine for indicating any variation in the tension of the driving band.

WILFRED WHITELEY.
